WRAPPING PAPER

Charles A. Pennock, Scarsdale, N. Y.

Application July 10, 1947, Serial No. 140,208

Term of patent 14 years

(Cl. D59—2)

To all whom it may concern:

Be it known that I, Charles A. Pennock, a citizen of the United States of America, resident of the city of Scarsdale, county of Westchester, and State of New York, have invented a new, original, and ornamental Design for Wrapping Paper, of which the following is a specification, reference being had to the accompanying drawing, forming part thereof.

The drawing represents a plan view of the wrapping paper showing my new design.

The design unit is outlined by broken lines and is repeated as indicated.

I claim:

The ornamental design for wrapping paper, as shown and described.

CHARLES A. PENNOCK.
